3 SHEETS-SHEET 3.

UNITED STATES PATENT OFFICE.

ROBERT J. BARR, OF ERIE, PENNSYLVANIA, ASSIGNOR OF ONE-HALF TO JOSEPH N. GERMAIN, OF ERIE, PENNSYLVANIA.

STEEL-GRIT BLAST-MACHINE.

1,089,388.

Specification of Letters Patent. Patented Mar. 10, 1914.

Application filed September 9, 1912. Serial No. 719,364.

To all whom it may concern:

Be it known that I, ROBERT J. BARR, a citizen of the United States, residing at Erie, in the county of Erie and State of Pennsylvania, have invented new and useful Improvements in Steel-Grit Blast-Machines, of which the following is a specification.

This invention relates to steel grit blast machines and consists in certain improvements in the construction thereof as will be hereinafter fully described and pointed out in the claims.

The object of the invention is to treat castings so as to remove the scale from them. In the present device the castings are subjected while being agitated to the action of steel grit under blast.

The invention is illustrated in the following drawings as follows:

Figure 1 shows a vertical section on the line 1—1 in Fig. 2. Fig. 2 shows an end view of the working parts, the outer plate of the frame being removed. Fig. 3 shows a top view of the machine. Fig. 4 a section of the nozzle and adjacent parts.

1 marks the tumbling barrel. The barrel is provided with a perforated peripheral shell and has the usual tracks 2 at its ends 30 which rest on the rollers 3 and 4, the rollers 4 being shown in dotted lines in Figs. 2 and 3.

The barrel is driven from rollers 3, these being rotated in the direction indicated by the dotted arrow in Fig. 2 so as to give to the side of the barrel above the rollers 3 an upward movement. This arrangement carries the castings within the barrel to a position above the rollers 3, therefore, the greater part of the weight of the barrel is supported by the rollers 3 so that the movement of the rollers 3 is readily conveyed to the barrel. The rollers 3 are fixed on the shaft 5, and the shaft 5 is journaled in the bearing 6 in the end plates 7^a and 8 of the frame. The rollers 4 are mounted on the shaft 9 and the shaft 9 is journaled in the bearings 10 arranged in the end plates 7^a and 8.

50 The frame of the machine is formed of the plates 7, 7^a and 8 referred to, the front plate 11, the rear plate 12, the top plate 13 and the bottom plate 14, the plates 11, 12, 13 and 14 forming an inclosure for the barrel and connecting the end plates to com-

plete the frame. The bottom plate 14 has the channels 15 arranged therein and so slanted as to carry the grit as it comes from the barrel to the sides of the machine where it is taken up and carried to position for 60 re-use by mechanism hereafter described.

The machine is driven by a pulley 16, the pulley 16 is fixed to a shaft 17 extending across the top of the machine. Shaft 17 is journaled in the bearing 18 in the plate 8, 65 and bearing 19 arranged on top plate 13. An outside bearing 20 is also provided for the shaft 17, the bearing 20 being fixed on the plate 21. The plate 21 is parallel to the plate 8 but separated therefrom. A 70 sprocket 22 is fixed on the outer end of the shaft 17, and this sprocket 22 is connected by a chain 23 (shown in outline) with a sprocket 24, the sprocket 24 being fixed on the shaft 5. Through the mechanism just 75 described the shaft 5 is driven and the barrel rotated.

The heads 25 of the barrel are stationary. They are separated from the plates 7 and 8 so as to make what is in effect a manifold 80 26 for the perforations in the ends. Tubes 27 lead to and from the faces 26 and are connected with means for effecting a scavenging circulation of air so as to carry off the dust as it is created in the barrel.

The castings in the barrel are apt to catch on the heads or between the end heads and the barrel shell. To obviate this the barrel is provided with the inwardly extending and slanting shoulders 28 and these shoulders acting on the castings throw the mass away from the ends of the barrel and thus prevent the danger of the castings catching on the heads or between the heads and the rotating part of the barrel.

A movable plate 30 is arranged opposite the plates 7 and 7^a and the plates 30 and 21 have the flanges 31 which extend to the plates 7, 7^a and so as to form an inclosed space between said plates. The grit as it is conveyed by the spouts 15 is deposited in the pockets 29, the plate 30 with its flange 31 having a supplemental inner plate 32 for completing this pocket, the plate 32 being secured to move with the flange 31. 100 The elevators 33 extend from the pockets 29 to the top of the space between the plates. The lower ends of the elevators run on the sprockets 34. The sprockets 34 are mounted on the shafts 35 and the shafts 105 36. The elevators 33 are arranged to move up and down in the space between the plates 7, 7^a and 30, the elevators 33 being secured to the flanges 31.

35 are carried by the bearings 36, these bearings being secured to the plates 21 and 30. The upper end of the elevator running in the space within the plate 21 runs over a 5 sprocket 37 and this sprocket is fixed on the shaft 17 and thus gives to this elevator its movement. The upper end of the elevator within the plate 30 runs over a sprocket 38. The sprocket 38 is fixed on 10 the shaft 39, and the shaft 39 is journaled in the bearing 40. The bearing 40 is carried on the plate 7. A clutch formed by the member 41 fixed on the shaft 39 and member 42 fixed on the shaft 17 is arranged 15 to drive the shaft 39 and thus the conveyer or elevator 33. The grit taken by these elevators from the pockets 29 is carried by said elevators and delivered to the hoppers 43 near the top of the machine, the walls 20 of the hopper being carried by the plates 30 and 21 and being of sufficient depth to form an inclosure with the plates 7 and 8.

The bottom walls 44 of the hoppers 43 are inclined so as to carry the grit toward the 25 wall adjacent to the barrel and the plates 7 and 8 have the curved surfaces 45 adjacent to the bottom of the hopper. The nozzles 46 are provided with flanges 47, the flanges having curved surfaces 48 corresponding to 30 the surfaces 45 of the plates 7 and 8. The nozzles are secured to plates 7 and 8 by screws 49 which extend through the slots 50 in the flanges 47 and into the plates 7 and 8. The nozzles have the usual hardened ends 35 which are removable. The air pipes 52 extend through passages 53 immediately above the bottoms 44 and extend into the nozzles so that when air is forced into the nozzles grit is entrained and carried through the 40 nozzles in the form of blast and delivered to the barrel. The passage 53 provides an air opening permitting an inflow of air through the hopper around the air pipe and this terminates adjacent to the nozzle. The air at 45 the nozzle injects air by way of the passage 53 and this prevents the arching of the grit at the bottom of the hopper and assures the continuous entraining of the grit by the air so as to permit a continuous blast.

50 The nozzles, clearly shown in Figs. 1 and 2, extend through the heads 25 of the barrel. They are arranged adjacent to the upward moving side of the barrel so as to deliver their blast upon the crest of the mass of the 55 castings as they roll over by reason of the upward movement of this side of the barrel. The nozzles are also so arranged as to be just above this crest and by means of the adjustment provided may be made to turn the blast directly to the crest thus formed so that all the castings as they turn in their rolling movement are subjected to the blast. It will also be noted that this arrangement 60 of the nozzles in connection with the roller support for the barrel leaves the body of the

barrel undisturbed so that the danger of castings clogging in the barrel as the barrel turns is obviated.

I provide a convenient means for shutting off the flow of grit from each nozzle. The 70 pipe 52 extends within the plates 30 or 21. A lever arm 55 is journaled by means of the pin 56 in the bearing 57, the outward movement of the lever being limited by a screw 58. The free end of the lever 55 is connected to a link 59 by means of a pin 60. The link 59 is connected to a clamp 61 by means of a pin 62. A lever 63 is fixed on the pin 56 provided with a handle 64. By means of this lever the air pipe may be forced into the nozzle 46 so as to close the nozzle against an outflow of grit. The outward position of the air pipe may be adjusted by the screw 58 so as to give the best results.

85 It will be noted that the nozzles 46 may be adjusted not only relatively to the supporting plate but also to the air pipe 52. In order to charge the barrel it is desirable to have one of the ends of the frame movable 90 so as to remove the head 25 of the barrel. In the present construction one end of the frame is hinged and carries with it one head of the barrel. The rear frame plate 12 is provided with the hinge lugs 65 and the 95 plate 30 has the hinge lugs 66 arranged to operate with the hinge lugs 65. Pintles 67 are provided for completing the hinge. The heads 25 are secured to the adjacent plates by the bolts 68 (see Fig. 4) radial distance 100 pieces 68^a spacing the head from the plate to form the manifold 26. The plate 7 is separated from the plate 7^a on a line with the opening of the barrel so that as the end frame is swung outwardly on the hinge the 105 plate 7 is carried with the frame plate 30 and the head 25 is carried with the plate 7. The elevator is also carried with this swinging frame, the clutch member 41 disengaging from the clutch member 42 to permit this 110 swinging movement. It will also be observed that the pocket 29 within the plate 30 is made complete in the swinging frame by means of the plate 32. When this frame is swung out the end of the barrel is open to 115 permit the removal of finished castings and the recharging of the barrel.

120 While I have designated my machine as a steel grit blast machine and so described it, it will be understood that any granulated abrasives other than steel grit may be used with the machine.

What I claim as new is:

1. In a steel grit blast machine, the combination of a barrel; means for rotating the barrel; a stationary head for said barrel; and a steel grit nozzle extending through said head adjacent to the side of the barrel having an upward movement and directed onto the crest of the material as it is formed

- by the rotating barrel, said nozzle terminating at a point adjacent to the head.
2. In a steel grit blast machine, the combination of a barrel, said barrel having a beveled shoulder adjacent to one of its heads; means for supporting and rotating said barrel; a stationary head within the beveled shoulder; and devices for delivering a blast to the barrel.
- 10 3. In a steel grit blast machine, the combination of a barrel; a steel grit blast nozzle directing a blast of grit to the interior of the barrel; perforated stationary heads for said barrel; and means for delivering a scavenging blast to one head and conveying said scavenging blast from the opposite head.
- 15 4. In a steel grit blast machine, the combination of a barrel; a steel grit blast nozzle directing a blast of grit to the interior of the barrel; perforated stationary heads for said barrel; and means for delivering a scavenging blast to one head and conveying said scavenging blast from the opposite head comprising a manifold for each head and 20 passages leading to and from said manifolds.
- 25 5. In a steel grit blast machine, the combination of a barrel; a head for said barrel; an end frame adjacent to said head; devices for elevating grit carried by said frame; means for movably supporting said frame, said means permitting the movement of said frame to permit the removal of the head of the barrel; and driving devices for said elevating means.
- 30 6. In a steel grit blast machine, the combination of a barrel; a head for said barrel; mechanism for driving the barrel; an end frame adjacent to said head; devices for elevating grit carried by said frame; means for movably supporting said frame, said means permitting the movement of said frame to permit the removal of the head from the barrel; and driving devices for 35 said elevating means, said driving devices being connected with the driving mechanism of the machine, the connection permitting the movement of the end frame.
- 40 7. In a steel grit blast machine, the combination of a barrel; a stationary head for the barrel; a frame adjacent to the head having a grit pocket at the bottom and a hopper at the top; an elevator carried by the frame for carrying grit from the pocket to the hopper; a mounting for the frame permitting the movement of the frame away 45 from the end of the barrel.
- 50 8. In a steel grit blast machine, the combination of a barrel; a non-rotatable head for the barrel; a frame adjacent to the head having a grit pocket at the bottom and a hopper at the top; an elevator carried by the frame carrying grit from the pocket to the hopper; and a mounting for the frame permitting the movement of the frame away 55 from the end of the barrel.
- 58 9. In a steel grit blast machine, the combination of a barrel; a removable head for the barrel; a frame adjacent to the removable head; a grit pocket and hopper in the frame; an elevator connecting the pocket and hopper; a shaft for driving the elevator; a drive shaft for the barrel; and a detachable clutch for connecting the elevator shaft with the drive shaft.
- 68 10. In a steel grit blast machine, the combination of a barrel; means for actuating the barrel; a stationary head for said barrel; a steel grit blast nozzle extending through said head; means for adjusting said nozzle relatively to said head, said means comprising curved supporting surfaces and curved flanges on the nozzle; and devices for securing the flanges to said curved surfaces.
- 78 11. In a steel grit blast machine, the combination of a barrel; means for actuating the barrel; a stationary head for the barrel; a nozzle extending into the barrel; means for adjusting the direction of the nozzle; an air pipe extending into the nozzle in position to entrain grit, said air pipe being free from the nozzle to permit the adjustment of the direction of the nozzle independently of the direction of the air pipe.
- 88 12. In a steel grit blast machine, the combination of a barrel; means for actuating the barrel; a stationary head for said barrel; a curved supporting plate for a nozzle; a nozzle having a curved flange secured to the said plate and extending through the head of the barrel and directing the blast to or near the side wall of the barrel.
- 98 13. In a steel grit blast machine the combination of a barrel; means for actuating the barrel; stationary heads for the barrel; blast nozzles extending through the heads and directioned to carry a blast of material adjacent to the side walls of the barrel.
- 108 14. In a steel grit blast machine, the combination of a barrel; a stationary head for the barrel; a grit hopper adjacent to the head; a nozzle extending directly from the hopper into the barrel; and means for delivering air to the nozzle to entrain the grit from the hopper.
- 118 15. In a steel grit blast machine, the combination of a barrel; a hopper adjacent to the end of the barrel; a nozzle leading from the hopper to the barrel; an air pipe leading to the nozzle in position to entrain grit from the hopper; and an air passage surrounding the air pipe and arranged to have a current or air induced through it by the action of the air from the air pipe to prevent the arching of grit adjacent to the nozzle.
- 128 16. In a steel grit blast machine, the combination of a barrel; stationary heads for

the barrel; end frames for the machine having grit pockets at their bottoms and hoppers at their tops; elevators for said frames for conveying the grit from the pockets to 5 the hoppers; nozzles extending from the hoppers through the heads of the barrel; and means for supplying an air blast to the nozzles.

17. In a steel grit blast machine, the combination of a barrel; stationary heads for the barrel; end frames for the machine having grit pockets at their bottoms and hoppers at their tops; elevators for said frames for conveying the grit from the pockets to 10

the hoppers; nozzles extending from the 15 hoppers through the heads of the barrel; and means for supplying an air blast to the nozzles, one of said frames being movable with its pocket, hopper and elevator for opening the end of the barrel. 20

In testimony whereof I have hereunto set my hand in the presence of two subscribing witnesses.

ROBERT J. BARR.
